FASTENING INSERTING MACHINE

Fred C. Eastman, Marblehead, Mass., assignor to
United Shoe Machinery Corporation, Paterson,
N. J., a corporation of New Jersey

Application June 8, 1932, Serial No. 616,063

17 Claims.

(Cl. 1—30)

This invention relates to fastening inserting machines and is illustrated herein as embodied in a machine arranged to sever fibre pegs from a strip of fibre material and to insert the pegs 5 in the sole portions of shoes.

When inserting fibre pegs to secure together parts of shoe bottoms it is often desirable that the lengths of the pegs be varied in accordance with the thickness of the different portions of 10 the shoe bottoms into which they are driven. This gives the pegs maximum holding power and insures that they will not pull out even from thin insoles. The heel seats of, for example Goodyear welt shoes, are nailed or pegged on 15 the last and, accordingly, it is impossible to caliper the thickness of the shoe bottom as might be done if the operation were performed off the last. It is practicable, however, as illustrated in United States Letters Patent No. 1,847,525, 20 granted March 1, 1932, on application of Fred C. Eastman and in United States Letters Patent No. 1,849,253, granted March 15, 1932 on application of Fred N. La Chapelle, to utilize the awl of a fastening inserting machine to measure 25 the thickness of shoe bottoms, the awl coming to rest when it meets an excessive resistance, as when it strikes an impenetrable member back of the shoe bottom, such as the metal heel plate or bottom plate of a last.

It is an object of the present invention to provide improved means applicable, for example, to machines of the type used for heel seat nailing, by which the awl may be permitted to come to rest without injury to the machine when the awl meets excessive resistance, for example, when the awl has passed through a shoe bottom and strikes the iron heel plate of a last on which the shoe is mounted.

In accordance with this object, a feature of 40 the invention comprises awl reciprocating mechanism including fluid means, illustrated as a hydraulic connection, serving to transmit work penetrating movement to the awl and arranged to yield to permit the awl to come to rest when the awl meets excessive resistance in its work 45 penetrating movement.

While the invention is illustrated herein as embodied in a fastening inserting machine particularly adapted to drive fibre pegs in sole portions 50 of shoes, for example, in heel seat pegging, it should be noted that the invention is not limited in its utility to such use or to embodiment in fastening inserting machines of the type illustrated and, accordingly, the machine disclosed 55 herein should be regarded as merely one exam-

ple of the forms in which my invention may be embodied.

With the above and other objects in view the invention will now be described with reference to the accompanying drawings and pointed out in the claims.

In the drawings, Fig. 1 is a side elevation of a machine illustrating one embodiment of the invention;

Fig. 2 is a side elevation with parts of the 10 machine cut away to show the fastening-feeding mechanism;

Fig. 3 is a view in front elevation of a preferred embodiment of the awl control mechanism;

Fig. 4 is a side elevation of the awl control mechanism;

Fig. 5 is a view partly in section taken along the line V—V of Fig. 3;

Fig. 6 is a cross sectional view taken along 20 the line VI—VI of Fig. 4;

Fig. 7 is a view partly in section taken along the line VII—VII of Fig. 3;

Fig. 8 is a view similar to Fig. 7 but showing the parts of the awl control mechanism in extended position;

Fig. 9 is a view in cross section taken along the line IX—IX of Fig. 4; and

Fig. 10 is an enlarged detail view showing the awl at the conclusion of its hole forming stroke.

The illustrated machine is of the general type disclosed in Letters Patent of the United States No. 1,030,775 granted June 25, 1912 on an application filed in the name of George Goddu, although organized to insert pegs severed from the strip of fastening material such as paper twine instead of loose nails. The machine may advantageously be equipped with a work support of the character disclosed in United States Letters Patent No. 1,686,808 granted October 9, 1928 on an application filed in the names of George Goddu and Fred L. MacKenzie. Reference may be had to these patents for a full disclosure of such parts as it is unnecessary to illustrate herein.

The illustrated machine is provided with a 45 column 10 which carries a head 12 on which are mounted the fastening inserting instrumentalities of the machine. The column 10 also carries a work support terminating in a last pin 14 (Figs. 1 and 2) arranged to support a work piece such 50 as a shoe 16 mounted on a last 18 with its sole 20 in engagement with a presser plate or abutment 22 carried by the head 12 of the machine. The shoe may be positioned relatively to the fastening inserting instrumentalities of the ma- 55

chine by a gage 24, which may be of any suitable form, also carried by the head 12 of the machine. Mounted in suitable bearings carried by the head of the machine is a cam shaft 30 carrying a cam member 32 provided with a series of cam grooves and surfaces arranged to operate the moving parts of the machine. Loose upon the cam shaft 30 near the rear end thereof is a pulley 36 driven from any suitable source of power by a belt 37. Slidably mounted on the shaft 30 is a clutch member 38 having a clutch surface 40 arranged for movement into and out of driving relation with a clutch surface 42 formed on the pulley 36. The clutch member 38 is also provided with a brake surface 44 arranged for movement into and out of braking relation with a brake surface 46 carried by the head 12 of the machine. A spring 50 surrounding the shaft 30 tends to move the clutch member 38 into driving relation with the pulley 36 but permits the clutch member 38 to be moved away from the pulley 36 and into engagement with the brake surface 46 by power transmitted from a cam 52 with which the cam member 32 is provided. The treadle rod 54 is depressed by a spring 55 upon the release of a treadle connected to the lower end of the rod 54. For a more complete disclosure of this mechanism which forms no part of the present invention reference may be had to United States Letters Patent No. 1,030,775 referred to above.

The machine is provided with a driver bar 60 mounted for reciprocating movement in vertical ways carried by the head 12 of the machine adjacent to the forward end of the shaft 30.

Clamped to the lower end of the driver bar 60 is a driver 62. The driver bar 60 is provided with a rack 64 meshing with a gear segment 66 formed upon the end of a forwardly extending arm of a bell crank lever 68 fulcrumed at 70 to the head 12 of the machine and having a depending arm carrying at its lower end a roll positioned in a cam track 72 formed in the cam member 32.

An awl bar carrier 80 is mounted for horizontal sliding movement in the front of the machine, and mounted for vertical sliding movement in ways formed in the awl bar carrier is an awl bar 82 carrying at its lower end an awl 84. The rear surface of the awl bar is provided with a rack meshing with a gear segment 83 formed upon the forward end of a lever 90 fulcrumed at 92 to the head 12 of the machine and provided with a pair of rearwardly extending arms 94 and 96. The awl carrier 80 is reciprocated transversely of the machine by a lever 100 fulcrumed to the head of the machine and carrying a roll positioned in a cam groove formed in the rear surface of the cam disk 102 secured to the forward end of the shaft 30. The arm 96 of the lever 90 is yieldingly and adjustably connected to a bell crank lever 104 fulcrumed at 106 to the head 12 of the machine and carrying a cam roll positioned in a cam track 108 formed in the cam member 32. Thus the awl 84 serves both to form fastening-receiving holes in a work piece presented thereto and to feed the work piece toward and past the driver 62 constituting a four-motion feed.

In order to permit the awl 84 to come to rest when it hits the metal bottom plate 110 of the last 18 the connection between the arm 96 of the lever 90 and the bell crank lever 104 includes a hydraulic connection which is so arranged that the connection moves as a unit until the awl meets an excessive resistance. The connection is provided with a system of spring-controlled valves, hereinafter to be described, which permit

the arm of the bell crank lever 104 to complete its movement without imparting any further movement to the awl 84.

The hydraulic connection includes a cylinder or sleeve 112 surrounding plunger 114 carried by a U-shaped support 113, the sleeve being carried by a link 115 connected to the bell crank lever 104 by a stud 116 and the plunger being connected to the arm 96 of the lever 90 by a set screw 118. The upper portion of the link 115 is slotted, as shown best in Figs. 7 and 8, for the reception of a threaded pin 117 by means of which the plunger 114 is connected to the U-shaped support 113, the pin 117 being held in position on the U-shaped support by nuts 119 threaded on each end of the arm 117. When the forwardly extending arm of the bell crank lever 104 is moved upwardly the plunger 114 and the sleeve 112 move upwardly as a unit but when the awl 84 strikes the bottom plate 110 of the last 18 the sleeve 112 continues its upward movement and the plunger 114, which is positively connected to the awl carrier 80, remains stationary. At the beginning of the relative movement of the plunger 114 and the sleeve 112 pressure is set up in a chamber 120 at the lower end of the sleeve 112. When a predetermined pressure is reached or set up the pressure on the oil or other fluid in the chamber 120 causes a valve 122 to be opened against the influence of a spring 124, thereby relieving the pressure and permitting the parts 112 and 114 to move relatively to each other. The valve 122 is seated in the lower end of a passage 123 in the sleeve 112 and is held against the seat by means of a spring 124. The tension of the spring 124 on the valve 122 may be adjusted by means of a hollow screw 126 into which the upper end of the spring 124 is pivoted. Relative movement of the sleeve 112 and the plunger 114 can thus be controlled by adjusting the tension of the spring 124. The oil which escapes from the chamber 120 past the valve 122 flows through a port 128 into a chamber or reservoir 130 above another valve 132 and the oil is stored in the reservoir 130 while the parts of the hydraulic connection are being returned to their original position. On return movement of the plunger 114 and the sleeve 112 the plunger 114 acts as a piston to decrease the pressure on the oil remaining in the chamber 120 which permits the valve 132 to open against the influence of a spring 134, thereby causing oil to flow into the lower end of the reservoir 130 and through a port 131 into the chamber 120, thereby filling the chamber 120 with oil when the sleeve 112 and the plunger 114 are returned to the position shown in Fig. 7.

In order to prevent leakage of oil past the lower end of the plunger 114, the lower end of the plunger is provided with packing 136 which is secured to the lower end of the plunger by a screw 138. The sleeve 112 is provided with openings 140 and 142 through which the device may be supplied with additional oil when necessary. The openings 140 and 142 are closed by means of cap screws 144 and 146 respectively to prevent loss of oil.

Since the valve 122 is provided with a spring which may be adjusted for various pressures it is evident that the hydraulic connection can be adjusted so that the awl 84 will penetrate a work piece such as a shoe bottom and stop when the awl strikes the metal plate 110 on the last 18.

The fibre fastening material 150 from which the pegs are formed is carried by a reel 152 mounted upon a bracket 154 secured to the head

12 of the machine. The strip 150 of fibre fastening material is engaged by a feed dog (not shown) of the feeding mechanism and by a spring-pressed holding dog designed to prevent retrograde movement of the fastening material after it enters a passageway, the lower end of which is in alignment with a driver passage of a forwardly and rearwardly reciprocating throat member 162 when the latter is in its rearmost position. Forward movement of the throat member 162 thus serves to sever a peg from the fastening material 150 and the length of this peg, as hereinafter described, is determined by the awl stroke, that is, by the distance which the awl has penetrated the work piece before being brought to rest by striking the metal heel plate 110 of the last. The throat member 162 is carried by the forward end of a bar 164 mounted for forward and rearward movement in ways carried by the head 12 of the machine and provided near its rear end with a rack 166 engaging a gear segment 168 formed on the lower end of a lever 170 fulcrumed at 172 to the machine head and provided with a roll positioned in a cam track 174 formed in the cam member 32.

The feed dog (not shown) is pivoted to the end of a pair of parallel links which are connected through a system of links and levers to the forward end of a lever 190 fulcrumed at 192 to the head 12 of the machine and having a rearwardly and upwardly extending arm 194 pivoted at 195 to the forward end of a link 196. The link 196 is pivoted intermediate between its ends to the forward end of another link 198, the rear end of which is adjustably pivoted by a bolt-and-slot connection 200 to a lever 202 fulcrumed at 204 to the machine frame and provided with a rearwardly extending arm carrying a roll positioned in a cam track 206. As illustrated, the lever 202 is effective also to transmit the pressure relieving movement to the work support 14 which facilitates the feeding of the work; that movement being transmitted through a rod 208 to mechanism of the character described in Letters Patent of the United States No. 1,587,848, modified, if desired, as shown in Figs. 23 and 24 of United States Letters Patent No. 1,686,808.

At its rear end the link 196 is provided with a slide member positioned in an arcuate slot 210 formed in the upwardly and rearwardly extending end of a lever 212 fulcrumed at 214 to the head 12 of the machine and having a forwardly extending arm 216 provided with a gear segment 218 meshing with a gear segment 219 formed upon the arm 94 of the lever 90. Thus it will be seen that the lever 212 will be brought through an angle which is determined by the extent of the reciprocation of the awl bar 82. The slot 210 has a radius of curvature equal to the effective length of the link 196 and the lever 212 is so positioned that the slot 210 is concentric with the pivot 195 between the lever 190 and the link 196 when the parts are in the position which they occupy when the entering end of the awl 84 is flush with the lower surface of the presser plate 22. As the awl 84 descends below this position, the lever 212 is rocked in a counter-clockwise direction as viewed in Fig. 2, the extent of this rocking movement depending upon the distance which the awl moves before it is stopped by impact with the metal plate 110 of the last 14. Thus, the rocking movement of the lever 202, which is uniform in each cycle of operation of the machine, is varied as it is transmitted to the lever 190, increasing with the increased eccentricity of the slot 210

relatively to the pivot 195 caused by an increased work penetrating movement of the awl 84. The bolt and slot adjustments 200 between the lever 202 and the link 198 permit the length of the fastening material to be increased a greater or lesser amount over the thickness of the work piece penetrated by the awl 84 so as to allow for a heading of the fastener which takes place if the fastening is somewhat longer than the thickness of the work in which it is inserted.

In the operation of the machine, the last 18 upon which the shoe 16 is mounted is placed on the last pin 14 of the work support, the shoe being positioned by the gage 24 in the manner usual in performing the heel seat nailing operation. When the machine is started, the awl 84 is thrust downwardly into the sole until its lower end comes substantially into contact with the metal plate 110 of the last. Preferably the awl is provided with a plane entering end formed at right angles to the longitudinal axis of the awl. When the awl 84 strikes the metal plate of the last, the valve 122 is opened, thereby permitting the sleeve 112 and the plunger 114 to move relatively to each other thus permitting the bell crank lever 104 to complete its rocking movement, as previously described, in a clockwise direction as viewed in Fig. 1, without further work penetrating movement of the awl and without the application to the awl of further power tending to produce such movement. The awl is then moved transversely, feeding the work piece and bringing the awl into the line of drive. The awl is then withdrawn and returned to the position which it occupied at the beginning of the cycle of operation. The work piercing or penetrating movement of the awl which has just been described is effective through the connection between the awl bar 82 and the lever 212 to rock the lever 212 in a counter-clockwise direction, as viewed in Fig. 2, to a position which is determined by the thickness of the work as measured by movement of the awl, thus controlling the angular relation between the link 196 on the one hand and the lever 212 and the link 198 on the other hand, so that the rocking movement of the lever 90 rocks the lever 180 to an extent sufficient to move the feed dog through a path sufficient to feed the fastening material a distance equal to or, if desired, slightly more than the thickness of the shoe bottom parts which the awl 84 contacts. The fastening material is severed by the forward movement of the throat member 162 and is brought forward into line with the driver 62 which descends to drive the fastening into the hole formed by the awl 84 in the shoe bottom.

Having thus described my invention, what I claim as new and desire to secure by Letters Patent of the United States is:

1. In a fastening inserting machine, means for forming a fastening receiving hole in a work piece, a movable operating member therefor, and connections between the operating member and the hole forming means, said connections containing a fluid and being arranged to yield against the resistance of said fluid when the hole forming means meets an excessive resistance.

2. In a fastening inserting machine, a reciprocating awl for forming fastening receiving holes in a work piece, an operating member for said awl, a co-operating plunger and sleeve connecting the awl and the member, and a fluid connection between the plunger and the sleeve.

3. In a fastening inserting machine, a reciprocating awl for forming fastening receiving holes

in a work piece, an operating member for said awl, a co-operating plunger and sleeve connecting the awl and the member, a by-pass about the plunger, and a valve yieldable in the by-pass constructed and arranged to permit fluid contained in the sleeve to pass from the sleeve when a predetermined pressure has been set up by the plunger.

4. In a fastening inserting machine, a reciprocating awl, actuating connections for the awl including a co-operating plunger and sleeve, and a fluid connection between the plunger and sleeve arranged to permit relative movement between the plunger and sleeve when the awl meets an excessive resistance.

5. In a fastening inserting machine, the combination of means for forming fastening receiving holes in a work piece presented thereto, means for reciprocating the hole forming means including a hydraulic member arranged to permit the hole forming means to penetrate the work piece but arranged to remain stationary relatively to the work when the hole forming means meets an excessive resistance, and means for inserting fastenings in said holes.

6. In a fastening inserting machine, an awl carrier, an awl carried thereby, and means for reciprocating the awl carrier thereby thrusting the awl into a work piece presented thereto and including a fluid connection serving to transmit reciprocating movement to the awl carrier, said connection being constructed to move as a unit during the work penetrating movement of the awl but arranged to yield when the awl meets an excessive resistance.

7. In a fastening inserting machine, the combination of an awl, means for operating the awl to form fastening receiving holes in a work piece presented thereto including a hydraulic connection movable as a unit to transmit work penetrating movement to the awl and arranged to yield when the awl meets an excessive resistance in its work penetrating movement, a driver, and means for operating the driver to drive fastenings into the holes formed by the awl.

8. In a fastening inserting machine, the combination of an awl carrier, an awl carried thereby, means for reciprocating the awl carrier including a fluid connected sleeve and plunger movable as a unit to transmit reciprocating motion to the awl carrier and arranged to maintain the plunger stationary when the awl meets an excessive resistance, and means for inserting fastenings in the holes formed by the awl.

9. In a fastening inserting machine, the combination of an awl carrier, an awl carried thereby, a plunger secured to the awl carrier, a sleeve surrounding said plunger, means connected to the sleeve for transmitting reciprocating movement to the awl carrier, fluid connections between said plunger and sleeve constructed and arranged to cause the plunger and sleeve to move as a unit when the awl is reciprocated to penetrate the work but arranged to permit the plunger and sleeve to move relatively to each other when the awl meets an excessive resistance, and means for inserting fastenings in the fastening receiving holes formed by the awl.

10. In a fastening inserting machine, the combination of an awl carrier, an awl carried thereby, a plunger secured to the awl carrier, a sleeve connected to the plunger, means connected to the sleeve for transmitting reciprocating movement to the awl carrier, hydraulic connections between said plunger and sleeve constructed and

arranged to cause the plunger and sleeve to move as a unit when the awl is reciprocated to penetrate the work but arranged to permit the plunger and sleeve to move relatively to each other when the awl meets an excessive resistance, a driver, means for operating the driver to insert fastenings in the holes formed by the awl, and means for presenting to the driver fastenings of a length corresponding to the depth of the respective holes formed by the awl.

11. In a fastening inserting machine, the combination of an awl, and means for operating the awl to form fastening receiving holes in a work piece presented thereto, said means including a hydraulically connected plunger and sleeve constructed and arranged to move as a unit during the work penetrating movement of the awl but constructed and arranged to move relatively to each other when the awl meets an excessive resistance in its work penetrating movement.

12. In a fastening inserting machine, the combination of an awl, power operated means for operating the awl to form fastening receiving holes in a work piece presented thereto, said means including a plunger connected to the awl, a sleeve connected to the power operated means of the machine, and valves constructed and arranged to cause the sleeve and plunger to move as a unit when the awl is penetrating the work but arranged when the awl strikes an excessive resistance to permit fluid contained in the sleeve to be passed out of the sleeve thereby permitting relative movement between the plunger and the sleeve.

13. A fastening inserting machine having, in combination, an awl carrier, an awl carried thereby, means for causing the awl to penetrate a work piece including a hydraulic connection movable as a unit and arranged to permit the awl to remain stationary when the awl meets an excessive resistance, a driver, and means for operating the driver to insert fastenings in the holes formed in the work piece by the awl.

14. In a fastening inserting machine, the combination of an awl, power operated means for operating the awl to form fastening receiving holes in a work piece presented thereto, said means including a plunger connected to the awl, a sleeve connected to the power operated means, and a valve constructed and arranged to remain closed to cause the sleeve and plunger to move as a unit when the awl is penetrating the work but arranged to open when the awl strikes an excessive resistance to permit fluid contained in the sleeve to be passed out of the sleeve thereby permitting relative movement between the plunger and the sleeve.

15. In a fastening inserting machine, the combination of an awl, power operated means for operating the awl to form fastening receiving holes in a work piece presented thereto, said means including a plunger connected to the awl, a sleeve connected to the power operated means, a valve and a spring for normally closing said valve to cause the sleeve and plunger to move as a unit when the awl is penetrating the work but arranged to yield when the awl strikes an excessive resistance to open the valve, thus permitting fluid contained in the sleeve to be passed out of the sleeve thereby permitting relative movement between the plunger and the sleeve.

16. In a fastening inserting machine, the combination of an awl, power operated means for operating the awl to form fastening receiving holes in a work piece presented thereto, said

- means including a plunger connected to the awl, a sleeve connected to the power operated means, and a valve constructed and arranged to remain closed to cause the sleeve and plunger to move 5 as a unit when the awl is penetrating the work but arranged to open when the awl strikes an excessive resistance to permit fluid contained in the sleeve to be passed out of the sleeve, thereby permitting relative movement between the plunger 10 and the sleeve, and a second valve constructed and arranged to remain closed during the work penetrating movement of the awl but arranged to open when the awl is withdrawn from the work to permit the fluid to pass into the sleeve.
- 15 17. In a fastening inserting machine, a reciprocatory awl for forming fastening receiving holes
- in a work piece, an operating member for said awl, a co-operating plunger and sleeve connecting the awl and the member, a by-pass about the plunger, a valve in the by-pass constructed and arranged to remain closed to cause the sleeve and the plunger to move as a unit when the awl is penetrating the work but arranged to open when the awl strikes excessive resistance to permit fluid contained in the sleeve to pass from the sleeve, and a second valve in said by-pass constructed and arranged to remain closed during the work penetrating movement of the awl and arranged to open when the awl is withdrawn from the work to permit the fluid to return to said sleeve. 10 15

FRED C. EASTMAN.
